United States Patent Office

Des. 224,384
Patented July 25, 1972

224,384

BATH BENCH

William R. Brewer, Arleta, Calif., assignor to Hamilton C. de Jong, Pasadena, Calif.

Filed Apr. 22, 1970, Ser. No. 22,554

Term of patent 14 years

Int. Cl. D6—01

U.S. Cl. D6—70

FIG. 1.

FIG. 4.

FIG. 3.

FIG. 1 is a left side perspective view taken from the front of a bath bench showing my new design;
FIG. 2 is a top plan view thereof;
FIG. 3 is a rear elevational view; and
FIG. 4 is a left side elevational view of the same.
I claim:
The ornamental design for a bath bench, as shown.
